UNITED STATES PATENT OFFICE.

HERBERT CUNNINGHAM MARTELL, OF CIRCLEVILLE, OHIO.

VEHICLE-BOOT.

SPECIFICATION forming part of Letters Patent No. 765,626, dated July 19, 1904.

Application filed October 22, 1903. Serial No. 178,057. (No model.)

To all whom it may concern:

Be it known that I, HERBERT CUNNINGHAM MARTELL, a citizen of the United States, residing at Circleville, in the county of Pickaway and State of Ohio, have invented certain new and useful Improvements in Vehicle-Boots; and I do hereby declare the following to be a full, clear, and exact description of the invention, such as will enable others skilled in the art to which it appertains to make and use the same.

This invention relates to vehicle-boots; and it consists of the novel construction and combination of the parts hereinafter fully described and claimed, whereby the boot-frame is held in position and prevented from rattling.

In the drawings, Figure 1 is a longitudinal section through a vehicle-body provided with a boot according to this invention. Fig. 2 is a plan view of the boot with portions of the boot-cover removed. Fig. 3 is a front view of the boot-spring.

A is a vehicle-body of any approved construction provided with a support b, which extends crosswise of it.

B is the boot-frame, which is hinged to the body by hinges c, arranged at about the top of the support b.

D is the cover of the boot, which is carried by the frame B.

E represents tubular guides which are secured to the side portions of the boot-frame.

F is the boot-spring, which is carried by the support b and which extends crosswise of the vehicle-body. This boot-spring has an eye or perforated lug g at its middle part and

is provided at its end portions with arms f, which extend rearwardly in the vehicle-body and engage with the guides E. 40

H represents brackets secured to the support b and in which the main portion of the spring is journaled.

I is an adjusting-screw which engages with the eye g and screws into the support b. A 45 space i is provided between the eye g and the cross-piece b, so that the said eye can be moved backward toward the cross-piece. The strength of the spring is adjusted by turning the screw, and the main portion of the spring 50 acts as a torsion-spring and presses the boot-frame downward onto the body and prevents the parts from rattling.

What I claim is—

The combination, with a vehicle-body provided with a cross-piece, and a boot-frame hinged to the said body; of bearings secured to the said cross-piece, a boot-spring journaled in the said bearings and provided with rearwardly-projecting arms at its ends and an eye 60 at its middle part arranged at substantially a right angle to the said arms, a space being provided between the said eye and the said cross-piece, guides secured to the said boot-frame and engaging with the said arms, and 65 a screw for adjusting the pressure of the said spring journaled in the said eye and engaging with the said cross-piece.

In testimony whereof I affix my signature in presence of two witnesses.

HERBERT CUNNINGHAM MARTELL.
